UNITED STATES PATENT OFFICE

ROBERT HAYBECK, OF PHILADELPHIA, PENNSYLVANIA

AIR MAIL EXCHANGE

Application filed July 3, 1930. Serial No. 465,515.

This invention relates to air mail exchange, and has for an object, to provide improved means for taking off and loading on mail, or like burden, to an aircraft.

5 A further object of the invention is to provide means, in the form of a tapered guide way, with means for rotating in accordance with the direction of the wind, and providing tapered means for releasing a sack of mail, or 10 the like, and improved means for taking up a sack of mail, or the like, arranged at the position of exchange.

A further object of the invention is to provide a device comprising spaced and converging guide members, terminating in adjacent parts forming a throat, through which a cable, from an aircraft may slide without hindrance, but providing means for releasing a burden carried by the cable, and providing 20 support for a cable attached to a burden at the location.

A further object of the invention is to provide a receptacle, preferably of foraminous material to offer sight obstruction to the wind, into which a burden may be deposited, with means for releasing the burden from a 25 depending cable, and with further means for automatically connecting the cable with a burden positioned at the location.

30 A further object of the invention is to provide an improved pick-up, which operates also as a release, for releasing a burden, and subsequently or simultaneously, picking up a second burden.

35 The invention therefore comprises a receptacle, preferably of tapered form, and of foraminous material, with a super-structure comprising converging guide members terminating in a throat, with a pick-up adapted to draw a burden into the receptacle and under the guide members, and to be released by the 40 throat or members carried thereby, and automatically pick-up a burden properly associated with the throat.

45 The invention is directed to other objects and possesses other features of novelty, some of which, together with the foregoing, will be hereinafter more fully set forth.

In the drawings:

50 Figure 1 is a view of the air mail exchange,

in side elevation, showing an aircraft in position for introducing a bag of mail, or the like, into the exchange apparatus,

55 Figure 2 is a top plan view of the apparatus,

Figure 3 is a view in side elevation, of the pick-up,

Figure 4 is a view of the pick-up in end elevation, as indicated by arrow 4 at Figure 3,

60 Figure 5 is a transverse sectional view through the pick-up, taken on line 5-5 of Figure 3,

65 Figure 6 is a detail view on an enlarged scale, showing in side elevation, a section of the guide at the throat,

Figure 7 is a transverse sectional view 65 through the guide member as on line 7-7 of Figure 6,

70 Figure 8 is a transverse sectional view through the guide member, showing the manner of attaching to the support as on line 8-8 of Figure 2, and

75 Figure 9 is a transverse sectional view through the guide member showing the manner of connecting the signal lights, as on line 9-9 of Figure 2.

Like characters of reference indicate corresponding parts throughout the several views.

78 The improved air mail exchange, which 80 forms the subject matter of this application, comprises preferably a frame work consisting of uprights 10, 11, 12 and 13. The guide posts, or uprights, 13, as will be noted especially from Figure 2, are spaced further apart 85 than the other uprights, and all is preferably mounted upon some means for rotating, as the turn table 14, with a manual lever 15, for rotating in accordance with the direction of the wind.

90 The uprights 11 and 12 have respectively curved beams 16 and 17 extending toward each other in pairs, as indicated more particularly at Figure 2. Erected upon the uprights 11, 12 and 13, are guide members 18, the ends of said members being supported directly upon the uprights 13, and intermediate parts supported upon the curved bars 16 and 17, providing extensions 18', preferably unsupported. These extensions 18' 100

are spaced apart to form a throat as indicated at Figure 2.

Underlying the structure of the guide members 18, is a receptacle comprising the bottom 19 and the side walls 19', and preferably composed of some foraminous material, as for instance, large mesh wire netting, although the invention is not limited to this specific type of fabric. This receptacle, while 10 substantially horizontal upon the top, tapers upwardly from the uprights 13, on the line 20, so that its outer edges are substantially supported at the uprights 11, with a curved or dished part 21 extending beyond 15 said uprights and supported upon a platform 22. The platform 22 is supported upon one side by uprights 11, and upon the opposite side by the uprights 10, and is preferably provided with a railing 23 for the safety 20 of an operative to be located upon the platform, a ladder 24 being provided for access.

The guide members 18, extending into, and continuing as, the extensions 18', are 25 preferably constructed of tubes open along their remote sides throughout their entire length. The opening is taken advantage of for the purpose of supporting the guide member. For this purpose, the curved bars 16 and 17 are constructed as shown at Figure 30 8, with a part 25 fitting within the arc of the tube and providing an opening 26, for the accommodation of electric wires 27. Spaced at any desired intervals, along the 35 guides 18, are a plurality of lights 28 which may be attached in any approved manner, provision here made by inserting a block 29 into the tubular guide members, carrying the socket 30, to which the electric wires 27 and the lights 28, are connected in the usual well 40 known manner. At the remote points of entrance, lights 31 and 32 are provided, and intermediate, a light under a protecting grating 33. It is intended that the lights 31 and 32 shall be red lights, and the light under 45 the protecting grating, a green light to indicate to the aviator the right position for entering into the exchange apparatus.

The platform 22 is also provided with lights 34 and 35 which are manually controlled in any usual well known manner. It is intended that one of these lights shall be red and the other green, the purpose being that if the delivery and pick-up shall be successfully accomplished, the attendant upon 55 the platform 22, will illuminate the green light as a signal to the aviator that the exchange has been properly made. If the exchange has not been properly made, the attendant will illuminate the red light which 60 shall be a signal to the aviator to return to make proper delivery or pick-up or both, as the case may be.

Co-operating with the structure above described, is a pick-up 36, which will be suspended, when exchange is to be made, by the

cable 37 from the aircraft 38. This pick-up comprises a hinged latch 39, so arranged as to engage a loop 40, formed by passing the cable 37 through the pick-up and return, as indicated at Figure 1, the loop 40 having been passed through the handle or other attaching part 41, of a mail bag or other burden 42. So long as the loop 40 remains engaged by the latch 39, the burden 42 will remain suspended or attached to the cable 37. 75

To release the latch and therefore the loop 40, a tube 43 is mounted to slide in the pick-up 36 and carries a detent 44 engaging a slot 45 in the latch, and provided with an inclined extremity 46, adapted when depressed, 80 not only to release the latch 39, but by the inclined part 46, to initiate the opening of the latch 39 upon its hinge.

Carried rigidly by the tube 43, is a plate 47 having upon its opposite sides, aprons 48, 85 such aprons being properly spaced to slide upon opposite sides of said pick-up. The plate 47 is supported by springs 49, with guide pins 50 slideable in the pick-up so that any weight or stress applied to the plate 47, 90 will serve to depress the tube 43 and therewith the detent 44, to release the latch 47, as before described.

The pick-up is preferably provided with oppositely extending horns 51, each curved 95 upwardly from the line of the plate 47, as shown in Figure 3.

Co-operating also with the burden 42, which is to be dropped, is the burden 52 which is to be picked up. This burden 52 is provided with a cable 53 of such length as to extend upwardly with sufficient slack to be inserted in the extensions 18', as shown more particularly in detail in Figure 6, being laid along for any desired distance inserted 105 through the guide members 18 upon opposite sides with a loop 53' extending outwardly beyond the ends of the extensions 18'.

In operation, when exchange of mail or other burden is to be made, the device is 110 rotated, if necessary, upon the turn table 14 so that the larger end, represented by the space between the uprights 13, is directed toward the wind, it being necessary, or at least 115 of greater convenience, that the airplane shall approach against the wind. The device being so located, the mail bag or burden 52 is applied, as above described, by raising the cable 53 and forming the loop 53' as noted. The device is now ready to receive 120 and deliver. The aircraft will approach along the median line of the device with the burden or bag 42 to be delivered dragging upon the ground, or suspended a short distance thereabove as circumstances may make 125 necessary or possible.

The continued movement will draw the bag 42 into the wider end of the receptacle 19 in a position below the guides 18. The continued motion will draw the burden up- 130

wardly along the inclined part of the receptacle 19 to the convergence of the guide members 18, and the cable 37 through the throat intervening between the extensions 18' with the pick-up 36 under these guide members. 5 As the cable 37 passes the ends of the extensions 18', the pick-up will be released from therebeneath to engage the loop 53' which will then partially embrace the cable 37 and sliding down, embrace the tube 43 and engage the plate 47 to release the latch 39, which in turn, releases the loop 40 and thereby and therewith, the burden 42. The pick-up engaging the loop 53' however, becomes 10 attached to the burden 52 so that this burden may be reeled into the aircraft for transportation. Such burden being reeled in, the cable will again be attached to the next burden and the several steps outlined repeated, 15 as often as exchange is to be made. 20

Of course, the air mail exchange, herein illustrated, may be modified in various ways without departing from the invention herein set forth and hereinafter claimed.

25 The invention is hereby claimed as follows: 1. An air mail exchange comprising an elevated platform, a bottom member declined from said platform to the ground level, side walls enclosing said platform and belled divergingly at the lower end of the bottom member, rails converging from points above the said ends of the side walls to form juxtaposed parallel sections above the platform, and top parts extending from the side walls 35 to the rails.

2. An air mail exchange comprising an elevated platform, a bottom member declined from said platform to the ground level, uprights along the remote edges of the bottom member, side walls supported by said uprights enclosing said platform and belled divergingly at the lower end of the bottom member, rails converging from points above the said ends of the side walls to form juxtaposed parallel sections above the platform, and top parts extending from the side walls to the rails.

3. An air mail exchange comprising an elevated platform, a bottom member declined from said platform to the ground level, side walls enclosing said platform and belled divergingly at the lower end of the bottom member, rails converging from points above the said ends of the side walls to form juxtaposed parallel sections above the platform, and top parts comprising brackets extending from the side walls to the rails.

4. An air mail exchange comprising an elevated platform, a bottom member declined from said platform to the ground level, side walls enclosing said platform and belled divergingly at the lower end of the bottom member, rails converging from points above the said ends of the side walls to form juxtaposed parallel sections above the platform,

and top parts covering the interval from the side walls to the rails.

5. An air mail exchange comprising an elevated platform, a bottom member declined from said platform to the ground level, side walls enclosing said platform and belled divergingly at the lower end of the bottom member, rails converging from points above the said ends of the side walls to form juxtaposed parallel sections above the platform, 70 said rails being formed as channels open along their remote sides, and top parts extending from the side walls to the rails.

6. An air mail exchange comprising an elevated platform, a bottom member declined from said platform to the ground level, side walls enclosing said platform and belled divergingly at the lower end of the bottom member, rails converging from points above the said ends of the side walls to form 80 juxtaposed parallel sections above the platform, said rails being formed as channels open along their remote sides, a cable loop having parts supported in the channels of said parallel sections, and top parts extending 85 from the side walls to the rails.

7. An air mail exchange comprising a turn table, a superstructure upon said turn table embodying an elevated platform, a bottom member declined from said platform to the ground level, side walls enclosing said platform and belled divergingly at the lower end of the bottom member, rails converging from points above the said ends of the side walls to form 95 juxtaposed parallel sections above the platform, and top parts extending from the side walls to the rails.

8. An air mail exchange comprising a turn table, a superstructure upon said turn table embodying an elevated platform, a bottom member declined from said platform to the ground level, uprights along the remote sides of the bottom member, side walls supported by said uprights enclosing said platform and belled divergingly at the lower end of the bottom member, rails converging from points above the said ends of the side walls to form 100 juxtaposed parallel sections above the platform, and top parts extending from the side walls to the rails.

9. An air mail exchange comprising a turn table, a superstructure upon said turn table embodying an elevated platform, a bottom member declined from said platform to the ground level, side walls enclosing said platform and belled divergingly at the lower end of the bottom member, rails converging from points above the said ends of the side walls to form 105 juxtaposed parallel sections above the platform, and top parts extending from the side walls to the rails.

10. An air mail exchange comprising a turn table, a superstructure upon said turn table embodying an elevated platform, a bot- 110

5 tom member declined from said platform to the ground level, side walls enclosing said platform and belled divergently at the lower end of the bottom member, rails converging from points above the said ends of the side walls to form juxtaposed parallel sections above the platform, said rails being formed as channels open along their remote sides, and top parts extending from the side walls 10 to the rails.

11. An air mail exchange comprising a turn table, a superstructure upon said turn table embodying an elevated platform, a bottom member declined from said platform 15 to the ground level, side walls enclosing said platform and belled divergently at the lower end of the bottom member, rails converging from points above the said ends of the side walls to form juxtaposed parallel sections 20 above the platform, said rails being formed as channels open along their remote sides, a cable loop having parts supported in the channels of said parallel sections, and top parts extending from the side walls to the 25 rails.

12. An air mail exchange comprising a turn table, a superstructure upon said turn table embodying an elevated platform, a bottom member declined from said platform 30 to the ground level, uprights along the remote edges of the bottom member, side walls supported by said uprights enclosing said platform and belled divergently at the lower end of the bottom member, rails converging 35 and inclined from points above the said ends of the side walls to form juxtaposed parallel sections above the platform, said rails being formed as channels open along their remote sides, and top parts extending from the side 40 walls to the rails.

13. An air mail exchange comprising a turn table, a superstructure upon said turn table embodying an elevated platform, a bottom member declined from said platform to 45 the ground level, uprights along the remote edges of the bottom member, side walls supported by said uprights enclosing said platform and belled divergently at the lower end of the bottom member, rails converging 50 and inclined from points above the said ends of the side walls to form juxtaposed parallel sections above the platform, said rails being formed as channels open along their remote sides, a cable loop having parts supported in 55 the channels of said parallel sections, and top parts extending from the side walls to the rails.

14. An air mail exchange comprising a turn table, a superstructure upon said turn 60 table embodying an elevated platform, a bottom member declined from said platform to the ground level, uprights along the remote edges of the bottom member, side walls supported by said uprights enclosing said 65 platform and belled divergently at the lower

end of the bottom member, rails converging and inclined from points above the said ends of the side walls to form juxtaposed parallel sections above the platform, said rails being formed as channels open along their remote 70 sides, a cable loop having parts supported in the channels of said parallel sections, and top parts covering the interval from the side walls to the rails.

75 In testimony whereof I have signed my name to this specification.

ROBERT HAYBECK.
